UNITED STATES PATENT OFFICE.

CARL OSCAR STONE, OF NEW YORK, N. Y.

DESIGN FOR A FLOWER-POT SUPPORT.

SPECIFICATION forming part of Design No. 32,288, dated February 27, 1900.

Application filed February 3, 1900. Serial No. 3,905. Term of patent 14 years.

To all whom it may concern:

Be it known that I, CARL OSCAR STONE, a citizen of the United States, residing at New York, in the county of New York and State 5 of New York, have invented and produced a new and original Design for Flower-Pot Supports, of which the following is a specification, reference being had to the accompanying drawing, forming part thereof.

10 The accompanying drawing represents a perspective view of a flower-pot support embodying my new and original design.

As shown in the drawing, the leading or material feature of my design comprises a plurality of straight uprights *a*, *b*, *c*, *d*, and *d'*, which are arranged in connection with an angular base-frame *e*, provided with a cross-brace *f*, a plurality of approximately-circular ledges or shelves *g* and *k*, the former having 15 oblong necks *h* and being connected with and all the same being supported by the several uprights. The uprights *a* are four in number and converge from the corners of the base-frame *e* to a point *j*, from which they diverge 20 upwardly. The upright *d'* projects vertically from the cross-brace *f*, meeting the uprights *c* at the point *j*. The uprights *c* project upwardly from the cross-brace *f*, approximately centrally thereof, and diverge, terminating

in a horizontal plane passing approximately 30 through the point *j*. The uprights *b* project vertically one from each of two opposite sides of the base-frame *e* and two from the cross-brace *f*, one projecting therefrom adjacent each end thereof. The ledges or shelves *g* 35 are arranged in three series, the first consisting of four thereof arranged approximately in the horizontal plane at the tops of the uprights *b*, the second series being arranged approximately in a horizontal plane, passing 40 through the point *j*, and the third thereof being arranged approximately in a transverse plane at the tops of the uprights *a*. A single ledge or shelf *k*, which is circular in form, is arranged at the top of the upright *d*. 45

Having fully described my invention, I claim as new and desire to secure by Letters Patent—

The design for a flower-pot support, substantially as shown and described. 50

In testimony that I claim the foregoing as my invention I have signed my name, in presence of the subscribing witnesses, this 1st day of February, 1900.

CARL OSCAR STONE.
